UNITED STATES PATENT OFFICE.

JOHN HAPPE, OF BROOKLYN, NEW YORK.

DESIGN FOR QUILTING.

SPECIFICATION forming part of Design No. 16,748, dated June 22, 1886.

Application filed January 24, 1885. Serial No. 153,937. Term of patent 7 years.

To all whom it may concern:

Be it known that I, JOHN HAPPE, of Brooklyn, county of Kings, and State of New York, have invented a new and original Design for Patterns for Quilting, of which the following is a full, clear, and exact description, reference being had to the accompanying drawing, making part of this specification, which represents a front view of a portion of a fabric quilted according to my design.

The design relates to quilting.

a a represent rows of diamond-shaped figures alternating with intermediate rows, *b b*, of diamond-shaped figures, the diamond-shaped figures of one row abutting at one side with the diamond-shaped figures of the other row, whereby a zigzag character is imparted to the design, the short diagonal axes of the diamonds forming straight lines at right angles to the lines on which the ends of the diamonds are in contact, as shown and described.

Having thus described my design, I claim as new and desire to secure by Letters Patent—

The design herein shown and described for quilting, the same consisting of rows or groups 25 of diamond-shaped figures, the ends of which are in contact, the diamonds being at angles to each other, whereby the shorter diagonal axes of the diamonds form straight lines at right angles to the lines on which the ends of the 30 diamonds are in contact, as shown and described.

In testimony that I claim the foregoing as my invention I have signed it this 22d day of January, 1885.

JOHN HAPPE.
